UNITED STATES PATENT OFFICE.

JAMES P. LA BAR, OF MILFORD, MICHIGAN.

HOISTING APPARATUS.

SPECIFICATION forming part of Letters Patent No. 229,149, dated June 22, 1880.

Application filed February 26, 1880.

To all whom it may concern:

Be it known that I, JAMES P. LA BAR, of Milford, Oakland county, Michigan, have invented an Improvement in Hoisting Apparatus, of which the following is a specification.

The nature of this invention relates to certain new and useful improvements in the construction of hoisting apparatus; and the invention consists in the peculiar construction, arrangement, and combinations of the various parts, all as more fully hereinafter set forth.

In the drawings, Figure 1 is a perspective view. Fig. 2 is an enlarged sectional detail.

15 In the accompanying drawings, which form a part of this specification, A A represent suitable standards, the upper ends of which are secured together by the side bars, B. A shaft, C, is journaled in proper bearings upon these bars B, and has rigidly secured to it the two ratchet-wheels D, between which is secured upon the shaft the spur-wheel E.

20 A forked lever, F, is pivoted to the shaft outside the ratchet-wheels, and has pivoted to it a pawl, G, which engages with the ratchet-wheels D. To one side of this pawl is secured one end of a rod, a, the opposite end of which is secured to a lever, H, pivoted to the lever F, as shown.

25 A ratchet or dog, I, is properly secured to the frame B, so as to engage with the ratchet-wheels, and has a rod, b, attached to one end of its shaft, which leads back to near the free end of the lever F, and is supported by an eye-iron, c, projecting from the side of such lever.

30 A windlass, J, is secured at the rear end of the frame, and is designed to operate a rope, K, to pull down the lever F.

A chain, L, the links of which engage with 40 the spurs on the wheel E, is placed over such wheel, and to one end are hooked the grapnel-hooks M by means of the chain N. This chain is secured at one end to one arm of the

hooks M, while the opposite end passes through an eye in the end of the other arm, 45 and is provided upon its end with a pin, g, which is passed through the link in the chain N, just outside of the eye of the grappling-hook M, through which the chain N passes after the hooks and chain have been adjusted 50 to grasp the object to be raised.

P is a lever pivoted to one of the grappling-hooks near its upper end, and provided with a hook, o, which is inserted in one of the links of the chain and operated to take up the 55 slack after the hooks have been adjusted to the weight to be lifted.

If desired, this frame may be mounted upon 60 wheels and advantageously used as a stump-puller or stone-wagon.

What I claim as my invention is—

1. The combination, with the grappling-hooks M, of the chain N, having the pin g at one end, and the lever P, pivoted to one of the 65 grappling-hooks and provided with the hook o, substantially as described, and for the purpose set forth.

2. In a hoisting apparatus, the frame A B, ratchet-wheels D, spur-wheel E, lever F, and pawl G, in combination with the dog I, windlass J, and rope K, substantially as and for 70 the purposes described.

3. In a hoisting apparatus, and in combination with the frame A B thereof, the ratchet-wheels D, spur-wheel E, lever F, pawl G, dog I, windlass J, rope K, chains L and N, and 75 grappling-hooks M, substantially as and for the purposes set forth and shown.

In testimony that I claim the above I hereunto set my hand this 26th January, 1880. 80

JAMES P. LA BAR.
